UNITED STATES PATENT OFFICE.

CHARLES SUMNER DU BELLE, OF WILLIAMSPORT, PENNSYLVANIA.

HAND STAMP MACHINE.

Application filed February 10, 1927. Serial No. 167,249.

This invention relates to hand stamp machines, and in the illustrated embodiments thereof the invention is shown applied to a dating machine, but the invention is not limited in its application to dating machines, as it is designed and adapted for general application to machines of different types, for example, numbering machines, check writing machines, printing presses and the like.

The primary object of the invention is to improve the construction and increase the efficiency and durability of machines of the character referred to.

Other objects are to provide simple and efficient means for applying ink to the type or printing wheels carried by the reciprocating plunger, and for throwing the ink-applying roller alternately into and out of position to contact with the face of the type during the reciprocating movement of the plunger, together with means for securing said roller in either of said positions during the stamping operation.

The invention will first be hereinafter more particularly described, with reference to the accompanying drawings, which are to be taken as a part of this specification, and then pointed out in the claims at the end of the description.

In said drawings, Fig. 1 is a vertical sectional side elevation of a hand stamp dating machine embodying my invention, showing the oscillating frame carrying the fluid inking reservoir and inking roller in its lowermost position;

Fig. 2 is a rear elevation of the same;

Fig. 3 is a vertical sectional side elevation; parts being broken away;

Fig. 3^a is a fragmentary view of the frame showing a detail;

Fig. 4 is a vertical sectional side view; the section being taken on the line 4—4 of Fig. 2;

Fig. 5 is a vertical sectional side view similar to Fig. 4 showing the oscillating frame in raised position;

Fig. 6 is a longitudinal sectional view of the fluid inking reservoir and associated parts;

Fig. 7 is a detail sectional view taken on the line 7—7 of Fig. 6;

Fig. 8 is a detail sectional view taken on the line 8—8 of Fig. 5;

Fig. 9 is a side elevation of a dating machine illustrating a modification of the device shown in preceding figures;

Fig. 10 is a similar view of said modification, looking at the opposite side of the machine;

Fig. 11 is a vertical sectional side elevation of said modification showing the oscillating frame in its lowermost position with the inking roller out of contact with the face of the type or printing wheels;

Fig. 12 is a detail sectional view of another modification in which the fluid inking reservoir is used for carrying and applying ink directly to the type or printing wheels;

Figs. 13 and 14 are detail sectional views showing a locking device for securing the plunger with the oscillating frame in raised position; and

Fig. 15 is a longitudinal sectional view illustrating a modification of the fluid inking reservoir.

In a pending U. S. application Serial No. 17,070, filed March 20, 1925, I have shown and described a machine embodying in its construction the essential and distinguishing features of the machine shown in the present case; this application being in large part a division of the aforesaid pending application and showing as the preferred construction a later development of the invention, improving and simplifying corresponding features or elements of the machine shown in the pending application.

In said drawings, in which the same reference letters are used to denote corresponding parts in different views, the letter A denotes the main supporting frame having mounted thereon a reciprocating plunger B, which is provided with a suitable handle and carries suitable printing devices or a printing wheel frame C, which is movable vertically therewith and carries type or printing wheels of ordinary construction with the usual means for operating the same; all of said parts being of well known construction so that they need not be specifically described herein.

On the inner sides of the upright members or legs of the frame A are formed vertical grooves a which, as shown in Figs. 4 and 5, are located at one side of the longitudinal center of the frame and receive studs or projections e on the printing wheel frame, (see

Fig. 2) which protrude through apertures in opposite side plates of an oscillating frame E to provide a vertically slidable pivotal connection between the supporting frame and said printing wheel frame and between the latter and said oscillating frame, the oscillating frame being fulcrumed at an intermediate point on the lower ends of pendant links D, which are pivoted at their upper ends to said main frame, so that on the reciprocating movement of the plunger an oscillatory movement will be imparted to the oscillating frame, throwing the latter frame into its uppermost position when the plunger descends and lowering it to the position shown in Fig. 4, on the upward movement of the plunger.

The oscillating frame E carries a fluid inking reservoir F and an inking or ink-delivering roller I adapted to contact with the printing means carried by the plunger on its upward movement for applying ink thereto; said reservoir being adapted to distribute ink upon the inking roller which in turn applies the ink to the type or printing devices.

The fluid inking reservoir has its bearings (as shown more clearly in Fig. 6) in the side plates of the oscillating frame to which are pivoted, on the inner sides thereof, between the ends of the inking reservoir and said side plates, swinging levers or rocker-plates G in which the shaft of the inking roller I has its bearings. The larger ends of the rocker-plates fit loosely on or around the trunnions or ends of the inking reservoir while opposite ends of the shaft of the inking roller I protrude through oblong slots in said side plates, so that the rocker-plates may be caused to rock or swing slightly on their pivots to throw the inking roller into or out of position to contact with the printing devices on the oscillatory movement of the oscillating frame. The fluid inking reservoir has secured thereon a body of absorbent material F¹ with which the inking roller contacts, and the inking roller, which is preferably made of rubber, is held normally in position to contact with the printing devices by spring-actuated means hereinafter described.

Each rocker-plate has formed therein at the end thereof adjacent the inking roller an opening in which is revolvably fitted a cam shaft K which is revolvably mounted in the side plates of the oscillating frame and carries a cam or cams k fitting in said openings, so that by rotating the shaft said cams will engage the rocker-plates and move the latter to throw the inking roller out of position to contact with the printing devices, or vice versa, according to the direction of rotation. A spring or springs H connected at one end with pins projecting inwardly from the ends of the rocker-plates opposite the inking roller and at the other end thereof with a trans-

verse rod or bar h passing through oblong slots in said rocker-plates and secured at opposite ends to said side plates, may be employed to hold the inking roller normally in position to contact with the face of the type or printing wheels on the downward movement of the oscillating frame until thrown into non-contacting position by the cam actuated means hereinbefore described.

The cam shaft K has its ends fitted in alined openings in the side plates of the oscillating frame and has fixed thereon or secured thereto at one end a resilient bow-shaped locking device L, one end of which bears against the adjacent side plate of the oscillating frame while the other end, of tooth-like form, engages one of a plurality of depressions or recesses in the adjacent side-plate and holds the rocker-plates relatively stationary with the inking roller normally in position to contact with the printing devices when the oscillating frame is moved by the plunger. By turning the cam shaft, the toothed end of the locking device will be caused to engage another depression in the adjacent side-plate and hold the rocker-plates with the inking roller out of contacting position, thus enabling the operator to throw the inking roller into position to contact with the face of the type or printing wheels or to prevent contact therewith when the oscillating frame is lowered. The cam shaft is preferably provided with a milled wheel K¹ on one end thereof by which it may be rotated when desired to shift the position of the inking roller.

As will be seen, when the plunger is depressed it will move the oscillating frame upon its shifting fulcrum, the studs e being guided along the vertical grooves a in the supporting frame and will throw the lower ends of the swinging links D outwardly, and as this movement is continued, the oscillating frame will be raised and with it the fluid inking reservoir and the inking roller, and thrown into the position shown in Fig. 5 out of contact with the face of the type or printing wheels, and on the reverse movement the inking-roller will contact with and apply ink to the face of the type.

The fluid inking reservoir F preferably consists of telescopically connected inner and outer tubular members f and f¹ each open at one end and closed at the other end thereof, and one or both provided with a filling aperture at its closed end; said filling aperture being closed by a removable stopper f²; but instead of concentric tubes the connected members of the inking reservoir may be of polygonal form in cross-section. Each member has minute orifices or pin holes therein which are arranged normally in separated relation but may be brought into registering position by adjusting or moving one member longitudinally upon or within

- the other in the direction of its axis. Preferably, each member is formed or provided at the closed end thereof with a radially projecting flange or other suitable means for 5 confining therebetween a cylindrical body F^1 of absorbent material surrounding the outer member and adapted to revolve therewith. Said absorbent body may consist of a cylinder of felt or other absorbent material of 10 sufficient thickness and width to span the space between the end flanges of the two members of the reservoir, but preferably it consists of a series of rings or sections of absorbent material surrounding the outer 15 member of the reservoir and secured together, as shown in Fig. 15, so as in effect to provide a solid body of cylindrical form within which the outer member of the reservoir is inserted.
- 20 The inner member of the inking reservoir is provided at its closed end with an exteriorly threaded axial extension f^3 which protrudes through an opening in the adjacent side plate of the oscillating frame E and has screwed thereon a nut f^4 having a 25 groove in its periphery to provide radially projecting flanges f^5 and f^6 between which is pivoted intermediate its length a substantially semi-circular locking device F^x , (Figs. 30 6 and 7) which carries at one end a stud or pin f^x adapted to enter a hole in the nut f^4 and engage a registering hole or socket in the axial extension f^3 , so as to cause the nut and extension to rotate together while permitting independent rotary movement of the 35 nut when said stud or pin is withdrawn from the socket or hole in said axial extension; such withdrawal being effected by pressure on the other end of said locking device 40 which carries a spring f^{xx} adapted to hold the stud or pin on the opposite end thereof normally in engagement with the hole or socket in said axial extension and to yield under pressure to permit the pin to be withdrawn. The peripheral flange f^6 on the 45 inner end of the nut f^4 is recessed to provide a shouldered portion of reduced width which fits within an annular groove provided by a correspondingly recessed and shouldered portion of a ring f^1 secured to the adjacent side plate of the oscillating frame E by set screws (as shown in Fig. 6) or other fastening means. The aforesaid 50 nut and axial extension have registering 55 holes therein to receive the pin f^x , so that the telescopically connected members of the inking reservoir may be adjusted axially one upon or within the other by withdrawing the pin and turning the nut until the pin snaps into another registering hole shown in the axial extension of the attached member of the inking reservoir.
- To impart rotary movement to the inking reservoir, a pawl or dog M having a tooth 60 m at one end is pivotally supported on one 65 of the swinging links D and adapted to engage a tooth of a ratchet wheel N when the oscillating frame is raised and impart a slight rotary movement to the ratchet wheel and through it to the inking reservoir and 70 the inking roller when the oscillating frame is lowered; said ratchet wheel being secured to a gear wheel O on one end of the shaft of the fluid inking reservoir in mesh with a smaller gear wheel O^1 on the adjacent end 75 of the shaft of the ink distributing or inking roller, so that when the inking reservoir is rotated, rotary motion will also be imparted to the inking roller; the inking reservoir and the inking roller being thus 80 caused to rotate in opposite directions.
- In order to render the machine noiseless in operation and to prevent jarring or injurious contact of the top of the printing wheel frame when raised by the plunger 85 with the underside of the cross-bar at the top of the supporting frame, said cross-bar has formed therein on the underside thereof sockets or recesses in which may be secured rubber pads P, adapted to serve as buffers 90 and eliminate noise and rattle.
- The supporting frame is preferably provided with a baseplate A¹ of rectangular form, and of greater width than the legs of the frame and provided with a rectangular opening therein to permit the face of the type or printing wheels to contact 95 squarely with the surface of the material on which an impression is to be made; said base-plate having upturned end-portions a^1 100 which are secured to the legs of the frame resting thereon by bolts or other fastening means, and the working parts of the device are suitably covered to protect them from dust and dirt, by means such as are usually 105 employed in machines of this type.
- In operation, the reciprocating plunger, which is held normally in raised position by spring-actuated means of ordinary construction, and automatically raised when free to 110 rise, is forced downwardly by the hand of the operator, causing the oscillating frame to swing upwardly along curved lines eccentric to the center of the ratchet wheel, and the pawl M, being held in position to 115 engage a tooth of the ratchet wheel N, will cause the latter to rotate when the oscillating frame is lowered and impart a slight rotary movement to the inking roller, and the inking roller will be slightly rotated by 120 the gears O and O^1 to bring a fresh portion thereof into contact with the surface of the absorbent body covered by the inking reservoir. On the reverse movement the pawl will 125 slide freely over the inclined teeth of the ratchet wheel for engagement with another tooth on the next return movement of the oscillating frame.
- The modification shown in Figs. 9, 10 and 130 11, is substantially identical with the con-

struction shown in my pending application, above mentioned; the side plates of the oscillating frame, which carries the fluid inking reservoir, being eccentrically fulcrumed 5 upon the legs of the supporting frame by means of pins or screws r inserted in interiorly threaded openings therefor in said legs and protruding into or through oblong slots R in said side plates; said slots being 10 inclined at an acute angle to longitudinally centrally disposed vertical grooves on the inner sides of the legs of the supporting frame, so that when the plunger is lowered the oscillating frame will be caused to swing 15 upwardly upon its shifting fulcrum, causing relative movement of the pivot pins c along the vertical grooves and moving the oscillating frame into the position shown in Fig. 10 of the drawings, with the inking roller out of 20 contact with the face of the type or printing wheels; the operation being substantially as hereinbefore described with reference to the operation of the machine shown in Figs. 1 to 5, and rotation of the inking reservoir 25 and inking roller being effected by similar pawl and ratchet mechanism, as shown in Fig. 10.

But in this modified construction, a roller I^1 is interposed between the inking reservoir 30 roller F and the inking roller I for spreading the ink evenly on the periphery of the reservoir roller and delivering the ink to the inking roller; said spreading roller being arranged in peripheral contact with the inking 35 roller and with the distributing or feeding surface of the fluid inking reservoir. This spreading roller I^1 is preferably composed of felt or other soft and absorbent material, while the inking roller is preferably composed of 40 rubber.

In this modification, the spreading and inking rollers are carried by oscillatory levers or rocker-plates G^1 which are pivotally secured to the side plates of the oscillating 45 frame on the inner sides thereof and carry at one end studs or pins g (see Fig. 11) which are connected by spiral springs H^1 with a transverse rod or bar h^2 connecting said side plates so that the spring or springs 50 will hold the inking roller normally in position to contact with the face of the type or printing wheels on the oscillatory movement of the oscillating frame. The rocker-plates or levers G^1 are forked at one end, as shown, 55 to receive cams or eccentrics k^1 on a cam shaft K^1 , whereby the position of the rocker-plates or levers may be changed to throw the inking roller into position to prevent contact thereof with the surface of the absorbent body carried by the fluid inking 60 reservoir, and vice versa, as desired.

The cam shaft K^1 is revolvably fitted in aligned openings in the side plates of the oscillating frame and provided at one projecting end with an operating lever or handle 65

k^2 having its free end turned inwardly to form a tooth adapted to engage depressions e^1 and e^2 in the outer side of the adjacent side plate of the oscillating frame E^1 , so as to secure and hold the inking roller in either 70 contacting or non-contacting position with the type, as desired. It will be yieldingly maintained in contacting position by the spring or springs acting on the rocker-plates to force the roller into contact with the type, 75 until the cam-carrying shaft is rotated in opposition to the force of the spring so as to throw the inking roller into position to prevent such contact. As shown, the cam-carrying shaft is in position to permit the spring to hold the inking roller normally in 80 contacting position.

The telescopically connected members of the fluid inking reservoir may be adjusted to bring the orifices therein in registering 85 position, or vice versa, and hold them in the desired position, by means such as hereinbefore described for that purpose with reference to Fig. 6 of the drawings, or a spring-pressed lever T pivoted to one of the 90 side plates of the oscillating frame and having a forked end engaging an annular groove f^{10} in an axial extension of one member of the inking reservoir may be employed for this purpose, as shown in Fig. 9; a spring 95 (not shown) being arranged between the side plate and the free end of the lever, so as to normally hold the lever in position to yieldingly hold the adjustable member of the inking reservoir with its orifices out of registering position with the orifices in the other member. 100

In the further modification shown in Fig. 12, the inking roller is dispensed with and the inking reservoir has its bearings in 105 rocker-plates G^2 fulcrumed at g^2 on the inner sides of the side plates of the oscillating frame E^2 and serves the double purpose of supplying ink and applying it to the face of the type or printing wheels; said inking reservoir being held normally in position to contact with the face of the type or printing wheels by means of a spring or springs H^2 connecting studs or pins on the inner sides 110 of the rocker-plates with a transverse rod 115 or bar carried by and connecting the side plates of the oscillating frame; said rod passing through oblong slots in the rocker-plates to permit a limited rocking movement of the latter. The rocker-plates G^2 are provided with openings therein through which the axes or axial extensions of the fluid inking reservoir project and pass through slightly enlarged registering openings in the side plates so as to permit a slight rocking 120 or oscillatory movement of the rocker-plates when desired to throw the inking reservoir 125 out of position to contact with the type or printing devices on the oscillatory movement of the oscillating frame. 130

Said rocker-plates also have alined openings therein to receive cams or eccentrics k^3 fixed on a cam shaft K^3 , by which the combined ink reservoir and inking roller may be 5 adjusted and held normally in position to either contact with the face of the type or printing wheels on the oscillatory movement of the oscillating frame, or out of contacting position, in a manner substantially as hereinbefore described.

In this further modification, in order to prevent the ink felt or absorbent body on the inking roller from gathering dirt or dust, I provide a cover for the inking roller comprising parti-cylindrical members U and U^1 , (Fig. 15) one of which encircles the roller, except at a point co-incident with the point of contact with the type, while the other is adapted to overlie said point, so that the 10 roller will be completely housed within the two members; the smaller member being 15 slidable upon the larger member in the direction of rotation to expose the roller at said point; said slidable member being provided with a handle v and having its ends 20 fitted in grooves formed in circular plates V having central openings therein fitting over the axial extensions of the fluid inking reservoir or roller, as shown in Fig. 15, and 25 forming with said parti-cylindrical members a drum-like structure in which the inking roller is enclosed.

In order to lock the plunger in lowered position with the oscillating frame raised, 30 and to prevent accidental disconnection by jarring when not in use, I may provide a safety lock comprising an eccentric or cam W (see Fig. 13) secured on the underside of the top cross-bar of the 35 supporting frame and adapted by partial rotation thereof to engage a shoulder at the base of a notch in the plunger rod B^1 , underneath said cross-bar, so as to prevent the plunger from being raised until released by 40 rotation of said eccentric disk; the latter being provided with a milled edge and secured in position by a set screw w as shown in 45 Figs. 13 and 14.

The inking reservoir, in the form shown 50 in Fig. 6 of the drawings, comprises inner and outer tubular members with orifices therein as hereinbefore described, which are fitted within a similarly perforated tube having end flanges between which the cylindrical body of absorbent material is confined. In the course of manufacture one 55 end of a perforated tube is first spun so as to form a radial end flange, whereupon the tube is inserted in the cylindrical absorbent body and then the other end of the tube is spun to form a radial flange at that end.

The housing shown in Fig. 15 is designed especially to protect the inking reservoir from dust and dirt when the machine is not 60 in use, and the several parts are assembled

by first placing the fluid inking reservoir inside of the larger member of the housing, which is then secured to one of the circular end plates V through a central opening in which an axial extension of the inking reservoir has been previously inserted, and thereupon the other circular end plate is fitted over the other axial extension of the reservoir and secured to said larger member by soldering or otherwise, whereupon the 70 smaller slidable member is fitted in the grooves provided therefor in said circular end plates, as hereinbefore described.

When using an inking reservoir having a cylindrical body of felt or other absorbent material in molded form surrounding the outer member of the reservoir, the absorbent body is preferably fitted upon a spun metal cylinder having end flanges spun thereon and of such size as to exactly fit 75 upon said outer member, as shown in Fig. 6, the outer tube of the reservoir or ink container being preferably ground so as to provide reduced portions or depressions between the end of the tube and an intermediate 80 peripheral enlargement of about four or five thousandths deep, in order that the ink passing through the orifices in the tubular members of the reservoir may flow freely and quickly around the outer tube; such construction also serving to prevent the ink 85 from working out under the ends of the spun metal cylinder and on and out along the aforesaid end flanges.

To admit light at the lower end of the 90 supporting frame, the upturned end portions a^1 of the base plate A^1 may be cut away in substantially U-shaped form, so as to provide openings therein co-incident with 95 openings formed in the lower ends of upright members or legs of the frame, as shown in the detail view Fig. 3^a.

Having thus described my invention, what I claim as new and desire to secure by Letters Patent of the United States is:—

1. In a hand stamp machine, a main supporting frame having mounted thereon a vertically reciprocating plunger carrying printing means, an oscillating frame having a vertically slidable pivotal connection with said plunger and a shifting fulcrum connection with said main frame; said fulcrum connection being provided by means of laterally swinging links pivoted at their upper ends to said main frame and at their lower ends to said oscillating frame, whereby the oscillating frame is adapted to swing upwardly away from the main frame on the downward movement of the plunger, and downwardly toward the main frame on the reverse movement of the plunger; said oscillating frame carrying means for applying ink to said printing means during its oscillatory movement.

2. In a hand stamp machine, a main sup-

- porting frame having mounted thereon a vertically reciprocating plunger carrying printing means, an oscillating frame having a vertically slideable pivotal connection with 5 said plunger and a shifting fulcrum connection with said main frame; said fulcrum connection being provided by means of laterally swinging links pivoted at their upper ends to said main frame and at their lower 10 ends of said oscillating frame at an intermediate point, whereby the oscillating frame is adapted to swing upwardly away from the main frame on the downward movement of the plunger, and downwardly toward the 15 main frame on the reverse movement of the plunger; said oscillating frame carrying a fluid inking reservoir and an inking roller normally in contact with said reservoir and adapted to contact with said printing means 20 during the oscillatory movement of said oscillating frame, and means actuated by the plunger for rotating said inking reservoir and said inking roller during said movements.
- 25 3. In a hand stamp machine, a main supporting frame having mounted thereon a reciprocating plunger carrying a printing wheel frame or printing means, an oscillating frame having a vertically slideable pivotal connection with said plunger and fulcrumed at an intermediate point on swinging supports pivoted to and depending from said main frame, so that said plunger on its reciprocating movement will impart an oscillatory movement to said oscillating frame; the latter frame carrying a fluid inking reservoir and an ink-applying roller adapted to contact with said printing means during said oscillatory movement, and means for rotating said inking reservoir on the downward movement of the oscillating frame.
- 40 4. In a hand stamp machine, a main supporting frame having mounted thereon a reciprocating plunger carrying a printing wheel frame or printing means, an oscillating frame having a vertically slideable pivotal connection with said plunger and fulcrumed at an intermediate point on swinging supports pivoted to and depending from said main frame, so as to provide a shifting fulcrum and adapt the plunger on its reciprocating movement to impart an oscillatory movement to said oscillating frame; the latter frame carrying a fluid inking reservoir and an ink-applying roller in contact therewith adapted to contact with said printing means during said oscillatory movement, and means for rotating said inking reservoir and said inking roller during said movements.
- 45 5. In a hand stamp machine, a main supporting frame having mounted thereon a reciprocating plunger carrying a printing wheel frame or printing means, an oscillating frame having a vertically slideable pivotal connection with said plunger and fulcrumed at an intermediate point on said supporting frame, so as to provide a shifting fulcrum and adapt the plunger on its reciprocating movement to raise and lower said oscillating frame; the latter frame carrying a rotary ink container and an inking roller normally in contact with said container and adapted to contact with said printing means on the reciprocating movement of the plunger, and means for rotating said ink container and said inking roller when the oscillating frame is lowered.
- 50 6. In a hand stamp machine, a main supporting frame having mounted thereon a reciprocating plunger carrying printing means, an oscillating frame having a vertically slideable pivotal connection with said plunger and fulcrumed at an intermediate point on said supporting frame so as to provide a shifting fulcrum adapting the plunger on its reciprocating movement to raise and lower said oscillating frame; the latter frame carrying a combined ink container and ink-applying device, the latter being adapted to supply ink to said printing means as said oscillating frame is actuated by the reciprocating movement of the plunger; and means for rotating said ink container and ink applying device when the oscillating frame is actuated.
- 55 7. A stamping machine comprising a reciprocating plunger mounted on a supporting frame and guided in its movements by means of studs or pins projecting into vertical grooves on the inner sides of upright members of the frame, an oscillating frame eccentrically pivoted to said plunger and having a shifting fulcrum or pivotal connection with said upright frame members, whereby said plunger, on its reciprocating movement, is adapted to impart an oscillatory movement to said oscillating frame; said plunger carrying printing devices and said oscillating frame carrying ink-applying means adapted to contact with said printing devices during said oscillatory movement; said ink-applying means including a roller having its bearings in rocker plates or levers which are pivotally supported intermediate their ends on the inner sides of side plates of said oscillating frame, spring-actuated means tending to force said roller into position to contact with said printing devices during said oscillatory movement, and means acting in opposition to the force of said spring-actuated means whereby said roller may be thrown out of position to contact with said printing devices or into position to contact therewith during the oscillatory movement of the oscillating frame.
- 60 8. In a machine of the character described, a supporting frame having mounted thereon a reciprocating plunger, an os-

positely disposed upright frame members, an oscillating frame having a vertically slide- 5 able pivotal connection with said plunger working in said guide-ways, whereby said oscillating frame is actuated by said plunger on the reciprocating movement of the latter; said oscillating frame comprising side-plates suspended from said main frame by swing- 10 ing supports having their upper ends pivoted to said main frame in a vertical plane out of the plane of said guide-ways and having their lower ends pivoted to said oscillating frame at an intermediate point so as to provide a fulcrum connection on which 15 the oscillating frame may swing upwardly away from said main frame on the down- ward movement of the plunger and inwardly 20 between said upright frame members on the reverse movement of the plunger; said plunger carrying printing means, and means 25 carried by said oscillating frame for applying ink to said printing means during its oscillatory movement; the latter means including an inking roller revolvably mounted in rocker-plates pivotally secured to the inner sides of said side-plates, and means 30 associated therewith for throwing the inking roller into or out of position to contact with said printing means on the oscillatory movement of the oscillating frame.

In testimony whereof I affix my signature.
CHARLES SUMNER DU BELLE.
